ABSTRACT OF THE DISCLOSURE

A hopper is movable vertically in a hoist tower to and from different positions for receiving material from a cable supported bucket and is releasably secured to tower posts or uprights in said positions by clamps carried on mounts slidably adjustable in relation to the hopper whereby a hopper of given depth and width may be employed effectively in towers of different plan dimensions.

This application is a continuation-in-part of our application Ser. No. 524,803, filed Feb. 3, 1966, Pat. No. 3,373,887, and pending application Ser. No. 621,310, filed Mar. 7, 1967, which is a continuation-in-part of said Ser. No. 524,803.

Known apparatus for a similar purpose has included a hopper which may be releasably secured at different operative positions vertically along a skeleton type tower and a bucket which, after loading, can be hoisted into position for discharging its contents into the hopper. However, in such apparatus, no provision is disclosed for using a hopper of a given or standard size in towers of different dimensions in plan. Accordingly, an object of the present invention has been to provide a hopper of standard depth and width, for example, which can readily be installed and effectively used in hoisting towers of conventional or other suitable skeleton type and of different dimensions in depth and width.

In general, an embodiment of our invention includes a hopper and bucket assembly, laterally extendable yokes slidably mounted on the hopper for adjustment toward and from posts of a hoist tower, arms mounted on said yokes to slide toward and from end positions thereon in a path normal to that of said yokes, clamps on said arms for releasable operative hopper supporting engagement with said posts when the arms are in one of said end positions, means for releasably securing said yokes in extended and retracted positions on the hopper, and means for releasably securing said arms in said end positions on said yokes.

Other objects and distinctive features of our invention not above referred to will appear from the following description and claims and from the accompanying drawings wherein we have shown a preferred embodiment of our invention.

In said drawings:

FIG. 1 is a top plan view partly in horizontal section of a bucket and hopper assembly (left hand side) with the parts shown in their relative positions when the hopper is in operative load receiving condition in a tower of relatively narrow width (full lines) and in a wider tower (dotted lines);

FIG. 2 is a view similar to FIG. 1 (right hand side) showing the corresponding parts in their relative positions when the hopper is releasably secured to travel with the bucket for vertical repositioning in the tower;

FIG. 3 is a horizontal section on the line 3—3 of FIG.

2

6 showing the hopper releasably secured to the tower in load receiving position;

FIG. 4 is a fragmentary view partly in vertical section from the line 4—4 of FIG. 3;

FIG. 5 is an end view with parts broken away to show the open ends of guide tubes arranged along inner surfaces of the front and rear walls of the hopper for receiving the spaced legs of slidably adjustable yokes which carry clamp supporting arms;

FIG. 6 is a front elevation of a hopper with parts broken away showing the arrangement of guide tubes and yokes as seen in FIGS. 1, 5 and 7;

FIG. 7 is an exploded view showing in perspective a yoke with legs withdrawn from the guide tubes and an end portion of a clamp carrying arm withdrawn clear of parallel guides mounted on the yoke.

Referring to the drawings, apparatus embodying the present invention is advantageously mounted to operate in quadrangular skeleton type towers of different plan dimensions represented in FIGS. 1 and 2 in part by the laterally spaced front posts 11 and 11' respectively. A hopper 12 is releasably secured to said posts at desired positions in the tower by clamps 13 and 14. A frame 17 of conventional or other appropriate construction is raised and lowered in known manner by a cable and hoisting mechanism not shown, said frame carrying a bucket 20 for delivering concrete or the like into the open upper end of the hopper.

Provision may be made for moving hopper 12 vertically to and from any desired level or operative load receiving position in the tower, where it is conveniently releasably secured by said clamps 13, FIG. 3, carried at the outer ends of arms 31 on upper yokes 50 and by clamps 14 carried at the outer ends by arms 33 on lower yokes 70, said yokes being axially slidably horizontally in hopper 12, FIG. 6. Means are also provided at the inner ends of said arms 33 for releasably coupling hopper 12 to be raised or lowered in the tower along with the frame, said arms 33, FIGS. 2 and 4, being axially slidably between end positions on guides 34 carried by yokes 70 in a manner to be described in more detail.

As seen in FIGS. 3 and 4, the axially slidable lower arms 33 are in extended position, or such as to permit clamps 14 at their outer ends to be closed around posts 11. Supplementary or upper arms 31, FIG. 3, carry clamps 13 which, along with clamps 14 on arms 33, normally support hopper 12 in operative position on the tower and which alone support said hopper while lower arms 33 are disconnected from said posts, FIG. 2, and are being moved to and from coupling relation to the frame and while yokes 70, FIGS. 6 and 7 are being axially positioned to facilitate such connection or to bring clamps 14 into operative clamping relation to the tower posts, FIG. 1.

In operation, when moving the hopper to a different level in a tower wherein the horizontal distance between the hopper supporting posts is greater than the width of the hopper, clamps 13 on arms 31 remain secured to posts 11' while clamps 14 on arms 33 are loosened from said posts; yokes 70 are moved axially inwardly to retracted position, solid lines, FIG. 1, and said arms 33 are moved rearwardly in guides 34 to bring their inner ends into the coupling position, FIG. 2, where said ends overlap plates 35 advantageously welded to outer upright edges of buttress plates 38 forming part of the bucket carrying frame 17 and having pin receiving holes 37. To secure arms 33 to frame 17, coupling pins 39 are pushed through holes 40 in said arms 33 and into holes 37 horizontally coaxial therewith in plates 35. This arrangement in effect releasably locks hopper 12 to the frame so that after said hopper is freed from the posts

11' it is supported by the cable, so that when said frame is raised or lowered thereby, said hopper is raised or lowered in like degree.

While the hopper is supported in effect by the hoisting cable, not shown, and the bucket frame 17, clamps 13 on arms 31 are disconnected from posts 11 or 11', as the case may be, and said supplementary arms 31 and clamps 13 are brought into disengaged positions or such that said clamps and outer end portions of said arms 31 avoid collision or contact with structural elements of the tower during vertical repositioning movement of the hopper.

When the hopper is brought to the desired new level, clamps 13 on supplementary arms 31 are closed around posts 11' to support the hopper while it is being uncoupled from the frame and being connected to posts 11' by clamps 14. To free the frame and bucket from the hopper when the hopper reaches this load receiving position, coupling pins 39 are withdrawn from holes 37 and 40; pins 51 are removed from their FIG. 2 position; and arms 33 are moved axially outwardly so that their inner ends disengage plates 35; pins 51 are placed, as seen in FIG. 1; yokes 70 are moved laterally to extended position where they are releasably secured by pins 59; and clamps 14 at their outer ends are closed around posts 11' with the hopper in load receiving condition as seen in FIG. 1.

To provide the above noted lateral adjustment of the slideable carriers as arms 33 of clamps 14 to accommodate a hopper of standard size to a tower which is wider than the hopper, the slideable yokes 70 comprise pairs of spaced parallel legs shown as rectangular tubes 52, each pair thereof being connected at their outer ends by a cross plate 53, FIG. 7. Inner end portions of said legs are mounted to slide horizontally in parallel guide tubes 54 provided on the insides of the front and rear walls of hopper 12, thereby permitting lateral adjustment of arm guides 34, lower arms 33 slideable thereon and clamps 14 to and from the dotted line or extended position of yokes 70 as seen in FIG. 1.

A similar arrangement is provided for supporting upper arms 31 which, with clamps 13, are slideably adjustable on yokes 50, FIGS. 3 and 6, to bring said clamps 13 into and out of clamping position in relation to the hopper supporting posts 11, 11, or 11', 11'.

As seen in FIG. 7, legs 52 of lower yokes 70 have sets of vertically coaxial holes 57 and 58 in their top and bottom walls positioned to receive pins 59 which also extend through coaxial holes in lower brackets 60 and in upper brackets 60' on the end walls of the hopper to releasably retain said yokes in one of different extended positions determined by the spacing between the hopper supporting posts of the tower in which the hopper is to be installed and used. Upper yokes 50, i.e. those which carry clamps 13, comprise parts having the same construction and mode of operation as those just above described in connection with yokes 70.

Where, for example, the tower posts are spaced apart laterally to an extent greater than the width of the hopper 12, as 11', 11', FIGS. 1 and 2, yokes 70 are extended laterally so that clamps 14 may be secured to said uprights 11'. Also, where the front to rear dimension of the tower is such that a space remains between the plane of the front wall of the hopper and the plane of hopper supporting uprights 11 or 11', arms 31 and 33 are extended forwardly to an extent such that coupling pins, as 51, can be engaged in holes 45 in guides 34 and holes in lugs on said arms, for example, when they come into coaxial vertical alinement, FIGS. 3 and 4. This arrangement permits use of a standard depth hopper in quadrangular towers having different dimensions in depth, assuming that appropriate horizontal spacing is provided between the holes 45 in the guides and 44 in the lugs which receive pins 51. Accordingly, arms 31 and 33 are provided with horizontally spaced lugs

43, 43' and 43", FIG. 4, having holes 44 which, when said arms are in their clamping positions, FIG. 1, are vertically coaxial with similar holes 45, FIG. 7, in guides 34, and receive pins 51. Said arms 33 are also conveniently held in said FIG. 2 coupling position by the headed coupling pins 51 extending through the appropriate holes in said lugs 43 when hopper 12 is coupled to the bucket frame.

As seen in FIG. 7, spacers 62 are provided on the end wall outer faces of hopper 12 to limit the inward movement of lower yokes 70, i.e. to leave a narrow gap between cross plates 53 and the hopper wall thereby to facilitate withdrawal of the yokes from retracted position in the guide tubes 54. Said tubes are conveniently formed by welding longitudinal edges of suitable channels to inner surfaces of opposed wall portions of the hopper, as the front wall 12a and rear wall 12b.

It is noted, FIG. 3, that arms 31 carry clamps 13 for releasable connection with front posts 11, 11, or 11', 11' and that, for such purpose, said arms 31 are slidably mounted on upper yokes 50 having cross plates 53', FIG. 3, in a manner similar to that of the mounting of arms 33 on lower yokes 70 having cross plates 53. Also, arms 31 are slideable to and from extended positions where they are conveniently releasably retained by pins 51, cooperating with coaxial holes in lugs 43, 43' and 43" and in guides 32. However, in the embodiment shows, only the arms 33 are equipped for coupling with the bucket frame; and arms 31 and clamps 13 serve to support the hopper, especially during the changeover to and from coupling of arms 33 with said frame.

As seen in FIG. 3, fixed clamp parts as 13', 14' are secured to arms 31 and 33, respectively, and cooperate with the detachable clamps 13, 14 to releasably secure said arms and hence their corresponding yokes to the posts 11, 11'.

In summary, when a hopper of the type above described is in load receiving condition in a tower having the space between its hopper supporting posts, as 11', 11', FIG. 1, greater than the width of the hopper, yokes 50 and 70 are both in laterally extended position and clamps 13 and 14 are releasably secured to said posts. However, when hopper 12 is coupled to the bucket supporting frame 17 during vertical repositioning in the tower, clamps 13 and 14 are free from said posts; yokes 70 are releasably secured in retracted position on the hopper by pins 59; and arms 33 thereon are secured in position with their inner ends in coupling engagement with said frame by pins 51. It thus appears that a single bucket-hopper assembly may advantageously be employed in material handling towers of different plan dimensions, whereas, in known apparatus, the choice may necessarily lie between using a tower of inappropriate plan dimensions to fit a given hopper, or incurring the substantial expense of a hopper of special plan dimensions to conform to special plan dimensions of a tower.

The described apparatus also functions to advantage where the front to rear dimension of the tower is such as to leave a substantial space between the plane of the hopper supporting posts, as 11', 11' and the plane of the front wall, as 12a of the hopper. In such case, the arms 31, 33 slideably mounted on yokes 50, 70, are extended to permit operative engagement of clamps 13 and 14 with posts 11', 11' or 11, 11, as the case may be. Said arms 33 are also releasably secured in such extended positions by pins 51.

It is noted that effective additional rigidity of the structure is provided by said pins 59 which releasably secure yokes 50, 70 to the hopper, and by said pins 51 which releasably secure arms 31, 33 to the guides on their respective yokes when said arms are in extended condition and releasably secure arms 33 to yokes 70 when arms 33 are coupled to the bucket frame. The above described provision for axially adjusting and securing arms 31, 33 on the yokes also applies advantageously where the width

of the space between posts 11, 11 is such as to require no lateral extension of said yokes to effectively retain clamps 13, 14 in post engaging position.

We claim:

1. Material handling apparatus comprising: a tower with a plurality of vertical posts, a bucket and a supporting frame therefor, means for raising and lowering said frame in said tower, a hopper releasably supported on posts of said tower and movable vertically along with said frame to and from different operative positions therein, and means for releasably securing the hopper in said operative positions, the improvement comprising clamp carrying yokes supported on said hopper, clamps mounted on said yokes, axially adjustable arms slidably mounted on said yokes, means mounting said clamps at the outer ends of said arms in position to engage said tower posts which are laterally spaced different distances apart, said arms being adjustable longitudinally on said yokes to different post-engaging positions depending on the extent or spacing between the hopper and the planes of the posts which support the hopper in load-receiving position, said yokes being slidably adjustable laterally on the hopper to move said clamps toward and from operative relation to the hopper-supporting posts.

2. Material handling apparatus according to claim 1 and wherein two sets of yokes are supported on the hopper, said arms on one of said sets of yokes being slidable in one direction to operatively connect the hopper with the frame for vertical movement therewith and in the opposite direction to disengage the frame and to bring the clamps into position to operatively engage said hopper-supporting posts of the tower.

3. Material handling apparatus according to claim 2 and wherein said arms on the other of said yokes are axially adjustable to bring the clamps thereon into and out of operative post engaging position to support the hopper while the clamps on said one set of yokes are disengaged from said posts.

4. Material handling apparatus according to claim 2 and wherein means are provided for releasably securing 40 said arms in their respective end positions on said yokes and for releasably securing said yokes in their respective end positions on the hopper.

5. Material handling apparatus according to claim 1 and wherein said hopper includes guide channels open at 45 their outer ends and in which said yokes are slidably engaged.

6. Material handling apparatus according to claim 2 and wherein arm supporting guides are mounted on said 50 yokes, and means are provided for releasably securing

said arms in different axial positions in relation to said supporting guides.

7. Material handling apparatus according to claim 1 and wherein said yokes include spaced parallel legs; and parallel guide tubes which open at their outer ends through opposed end walls of the hopper are positioned within said hopper on interior portions of opposed front and rear walls thereof, inner end portions of said legs of the yokes being slidably telescoped in said guide tubes.

8. Material handling apparatus which provides an open top hopper having front and rear walls and opposed end walls and being releasably and adjustably supported on vertical posts of a skeleton hoisting tower to receive material discharged from a vertically movable bucket, and wherein the improvement comprises a set of clamp-carrying yokes, each yoke including parallel legs joined at their outer ends by a connector plate, a set of leg receiving guide tubes each having an open end exposed through one of said end walls one of said tubes being positioned on said front wall and the other on said rear wall, said yokes being mounted with inner end portions of said legs axially slidable in said guide tubes, and clamping means mounted on said connector plates and laterally adjustable therewith toward and from operative clamping position in relation to said vertical posts of the tower.

9. Apparatus according to claim 8 and wherein a second set of guide tubes is positioned on said front and rear walls of the hopper, and a second set of yokes having clamp carrying connector plates is mounted with inner end portions of the legs thereof axially slidable in said second set of guide tubes, clamping means carried on the connector plates of said second set of yokes and arranged and adapted to support the hopper on said posts when the clamping means on the first set of yokes are released therefrom.
